UNITED STATES PATENT OFFICE.

CHARLES WILLIAM OWENS, OF PONTARDawe, WALES.

DOMESTIC HOT-WATER-SUPPLY SYSTEM.

1,372,540.

Specification of Letters Patent. Patented Mar. 22, 1921.

Application filed May 18, 1920. Serial No. 382,424.

To all whom it may concern:

Be it known that I, CHARLES WILLIAM OWENS, a subject of the King of Great Britain, residing at Pontardawe, in the 5 county of Glamorgan, South Wales, Great Britain, have invented certain new and useful Improvements in Domestic Hot-Water-Supply Systems, of which the following is a specification.

10 This invention relates to improvements in domestic hot water supply circulating systems of that kind in which the usual hot water storage tank or circulating cylinder is dispensed with, and the object of the 15 present invention is to provide a construction or arrangement in which a substantially open supply cistern, at a sufficient elevation is employed connected with a pressure boiler by means of flow and return 20 pipes, but into which cistern cold water from the main water supply shall not be directly admitted as has usually been the case.

According to the present invention it is 25 proposed to employ an open cistern at a sufficient elevation and to connect such a cistern by flow and return pipes directly to the pressure boiler, but in order that the cold water supply shall not be admitted directly 30 into said cistern the cold water inlet is connected by means of a suitable communicating pipe to the return pipe leading to the pressure boiler. The said cold water inlet is governed by a ball cock in the usual manner.

35 With this arrangement it will be readily seen, the ordinary circulation through the flow and return pipes and the pressure boiler will not be interfered with, but the admission of the cold water to the return pipe will effectually prevent the said cold water mixing with the hot water already in the cistern when the system is in operation and moreover will induce a more rapid circulation 40 through the pressure boiler. A larger supply of hot water will by this means be available owing to the fact that the cold water supply to the cistern passes firstly through the pressure boiler before it reaches 45 the cistern and thus substantially the whole contents of the said cistern can be drawn off before the water contained therein becomes appreciably cooler.

50 In order that the invention may be clearly understood reference is made to the accompanying drawing in which Figure 1 is a sec-

tional view of a storage cistern showing the improvements according to this invention, and Fig. 2 is a diagrammatical view showing the improved storage tank and its 60 connections to a domestic hot water supply circulating system.

In these figures, 1 represents a cistern or tank of usual and known construction. This cistern has a detachable cover 2, which 65 may be provided with an air or steam vent 3. The usual cold water inlet pipe 4 is connected with the main supply and has a ball cock 5 for controlling the admission of cold water and 6 is an overflow pipe. 7 and 8 70 are the flow and return pipes respectively to the pressure boiler 9, and 10 is a pipe through which the house supply may be drawn off. This pipe 10 is connected to the cistern 1 at a point just above the level of 75 the ends of the flow and return pipes 7 and 8 where they enter the cistern 1 in order that the water may never fall below the tops of the said flow and return pipes 7 and 8 as the house supply is drawn off, owing 80 to the main supply being cut off by frost or other unforeseen circumstances.

To the return pipe 8 at a point 11 just below its inlet end in the cistern 1 a vertical pipe 12 is attached, the upper end of 85 said pipe 12 having a funnel shaped mouth-piece 13 situated just below the cold water inlet 4 and above the high water level 14 in the cistern 1. A supply of cold water to the system is thus permitted without said 90 water supply entering the cistern 1 until it has first passed through the high pressure boiler 9. Of course it is obvious that instead of providing the pipe 12 with a funnel top 13, the said pipe 12 might be directly attached or connected to the ball valve 5 by a screw union or other means although the form shown is preferred by reason of its accessibility.

95 From the foregoing description it will be 100 readily seen that practically the whole of the contents of the cistern 1 could be drawn off before there would be any appreciable diminution in the temperature of the water contained therein, that an improved circulation will be obtained and that the ordinary circulation of the water through the system will not be interrupted.

105 What I claim as my invention and desire to secure by Letters Patent is:—

110 1. In a domestic hot water supply circulating system having an open tank serving

as a hot water storage and supply cistern, a pressure boiler, flow and return pipes between said pressure boiler and said storage and supply cistern; the combination of a float-governed cold water supply valve within said tank and a communicating pipe connecting the cold water supply valve with the return pipe at a point below the upper end of the said return pipe, to supply cold water directly to said return pipe.

2. In a domestic hot water supply circulating system having an open tank serving as a hot water storage and supply cistern, and a pressure boiler, the combination of flow and return pipes between said pressure boiler and said storage and supply cistern having open ends within said cistern, and a float-governed cold water supply valve within said cistern and a communicating pipe connecting the cold water supply valve with the said return pipe of the system at a point below the upper open end of the said return pipe and within said storage and supply cistern to supply cold water directly to said return pipe, the open ends of both said flow and return pipes projecting within said open storage and supply cistern.

3. In a domestic hot water supply circulating system, the combination with an open tank serving as a hot water storage and supply cistern, a pressure boiler, flow and return pipes between said pressure boiler and said storage and supply cistern, of a float-governed cold water supply valve within said cistern; a vertical pipe within the cistern connected at its lower end to said return pipe at a point below the open end of said return pipe and within said storage and supply cistern, the open ends of said

flow and return pipes projecting within said open storage and supply cistern, a funnel shaped mouthpiece fitted to the upper end of said vertical pipe and located above the high water level of said storage and supply cistern and having the outlet of said cold water supply valve located within the said funnel shaped mouthpiece of said vertical pipe, to supply cold water directly to said return pipe.

4. In domestic hot water supply circulating systems having an open tank serving as a hot water storage and supply cistern, a pressure boiler, flow and return pipes between said pressure boiler and said supply cistern, and a float-governed cold water supply valve; a vertical pipe connected at its lower end to said return pipe at a point below the open end of said return pipe and within said storage and supply cistern, the open ends of said flow and return pipes projecting within said open storage and supply cistern, a funnel shaped mouthpiece fitted to the upper end of said vertical pipe and located above the high water level of said storage and supply cistern and having the outlet of said cold water supply valve located within the said funnel shaped mouthpiece of said vertical pipe, and a hot water delivery pipe connected to said cistern above the level of the open ends of said flow and return pipes within the said cistern.

In witness whereof I have hereunto set my hand in the presence of two witnesses.

CHARLES WILLIAM OWENS.
